UNITED STATES PATENT OFFICE.

CHARLES H. JENNE, OF INDIANAPOLIS, INDIANA, ASSIGNOR OF ONE-HALF
TO NORMAN S. BRADEN, OF SAME PLACE.

STATION AND STREET INDICATOR.

SPECIFICATION forming part of Letters Patent No. 406,170, dated July 2, 1889.

Application filed December 17, 1888. Serial No. 293,767. (No model.)

To all whom it may concern:

Be it known that I, CHARLES H. JENNE, of Indianapolis, Marion county, and State of Indiana, have invented certain new and useful 5 Improvements in Station and Street Indicators; and I do hereby declare the following to be a full, clear, and exact description of my invention, such as will enable others skilled in the art to which it appertains to make and 10 use the same.

My invention relates to the class of indicators known as "station and street indicators," of which the devices illustrated and described 15 in my former patents—viz., street and station indicators, patented March 18, 1884, No. 295,405, and February 3, 1885, No. 311,586—are examples.

The object of this invention is to improve 20 the devices heretofore mentioned and provide my new device with mechanism simple in construction to operate successfully an apron for 25 successively indicating at the proper times the stations or crossings to which the street-car, steam-car, or steamboat is approaching, and in the same time displaying to the passengers thereon the names of such streets, 30 corner numbers of houses, and advertisements of business-houses as may be placed upon the apron located on street-corners or stations along the route of travel of cars or steamers; and it consists in the construction hereinafter 35 described and illustrated in the drawings, and more particularly related to in the claims.

In the drawings filed herewith, Figure 1 is 40 a front view of my indicator. Fig. 2 is an end view of the same. Fig. 3 is a view of Fig. 1, the lid 2 being removed and exhibiting the interior working parts of my indicator, partly in elevation and partly in sectional view. Fig. 4 is a sectional side view of Fig. 3. Fig. 5 denotes a portion of my device in top view. Fig. 6 is an enlarged detail view of my invention, hereinafter set forth. Fig. 7, Sheet 2, is 45 a portion of an enlarged sectional side detail view of parts of my invention—namely, roller 4. Fig. 8 represents a top view of Fig. 7, partly sectional and partly in top view.

In Fig. 1, 1 represents the apron having printed thereon the name of a street and the 50 corresponding number of the street where the business-house is located and the name of

said house is illustrated, a space sufficient to expose said names having been provided in the lid 2.

4 and 5 denote rollers loosely journaled into 55 the casing 3, and serve for winding and unwinding apron 1 by the mechanism hereinafter described.

6 and 7 denote hollow journals or spindles firmly driven into the hollow corresponding 60 openings of rollers 4 and 5, and extending laterally through the partition-wall 10.

8 and 9 are sprocket-wheels loosely mounted over the hollow spindles 6 and 7, and said sprocket-wheels are provided on the inner side 65 and facing the rollers 4 and 5 with teeth such as are used in crown-wheels. The peripheries of said wheels are provided with sprockets to receive the endless sprocket-chain 20, to impart motion to rollers 4 and 5. 70

11 and 12 are catch-pawl inserted loosely into the ends of rollers 4 and 5, the long vertical arms of which are hinged at 13 and 14. The other horizontal arms are extended out of the rollers, and are made to engage with the 75 crown-teeth of the sprocket-wheels 8 and 9 by means of the connecting-rods 16 and 17, which rods are centrally located in the hollow spindles 6 and 7, and are held in position therein by being hinged on one end to the catch-pawls 11 and 12, and the other end by an opening provided in case 3, which serves as a support for said rods. By moving the inclined plates to and fro and having loosely inserted the ends of rods 16 and 17, provided with 80 shoulder and nut, into the slotted portion of said plates 19, a lateral motion to the rods is derived, forcing catch-pawl 13 and 14 alternately into and out of engagement with crown-teeth of the sprocket-wheels 8 and 9. 85

21 in Figs. 3 and 4 is a block made of iron, wood, or other material, and is inserted into a compartment provided for this purpose. On the upper end of this block is attached the end of a rope 22, which passes through the 90 case 3 over pulleys to the party operating the same. A crank-shaft 23 passes through said block 21, and said shaft is provided on the inner end with a yoke-lever 24. (See enlarged view, Fig. 6.)

28 is a V-shaped spring inserted into an aperture in block 21, pressing against a stop- 95

pin 27, projecting upward on crank-shaft 23. By turning the handle of the shaft the pin 27 will rotate with the same and keep one arm of the yoke in engagement with the corresponding side of the endless chain 20. As can readily be seen, this block 21, pulled upward and being engaged with sprocket-chain 20 by one arm of the yoke 24, serves to transmit a rotary motion to the rollers 4 and 5.

10 The mode of operating my device is as follows: Having fastened my indicator on the proper place in a street-car, steam-car, or steamer, and provided the same with the apron and operating mechanism as illustrated and described, (and I intend to indicate the approaching street-corner, corner-number, or business-house so indicated on the apron,) I move the handle of crank-shaft 23 partly to the left, (see Fig. 2 in dotted lines,) engaging the yoke with the sprocket-chain 20, and also the inclined plates in the same direction, thus throwing into engagement the upper catch-pawl 12 with the crown-teeth of the sprocket-wheel 8. Now, by pulling the block 21 upward by the rope 22, 15 I rotate the roller 4 and bring into view the desired name or number of the street-corner and advertisement printed on the apron. By releasing the rope 22 the block 21 on account of its weight will drop downward, striking an 20 annunciator by a suitable device, and so calling the attention of passengers to such station, &c. At or near the next station or corner of a street the same manipulation is repeated until the car, street-car, or steamer arrives at the end of the route. On returning I reverse the action of inclined plates and yoke, and thus liberate roller 4 and engage roller 5.

Having described my invention in such a manner that those familiar with indicators can construct and operate the same, what I claim as new, and desire to secure by Letters Patent, is—

1. In an indicator of the character described, the main casing, a vertical gravitating block at the side thereof, a crank-shaft passing through said block, and a yoke-lever on the inner end thereof, in combination with rollers within said casing, an apron on said rollers, for the purpose set forth, and means 45 for imparting rotary motion to said rollers.

2. In an indicator for street-cars, &c., the main casing, rollers therein, sprocket-wheels mounted on the ends of said rollers, and an endless sprocket-chain engaging said sprocket-wheels, in combination with a block located 55 at the side of the main casing and formed with an opening, a V-shaped spring in said opening, a crank-shaft having an upwardly-projecting pin adapted to engage said spring, a yoke-lever secured on the inner extremity of 60 said crank-shaft, and a rope or chain having its end secured to said block, all substantially as and for the purposes set forth.

3. In an indicator for street-cars, &c., the main casing, rollers journaled therein, hollow 65 spindles at the extremities of said rollers, and an apron connecting said rollers and adapted to serve the purpose specified, in combination with sprocket-wheels mounted on said spindles and having their inner faces formed 70 with crown-teeth, an endless sprocket-chain engaging said sprocket-wheels, and pawls, one member of each of which is pivoted within one of said hollow spindles, and the other member extends out therefrom and is 75 adapted to engage the crown-teeth of one of said sprocket-wheels, as set forth.

4. In an indicator for street-cars, &c., the main casing, rollers mounted therein and located one above the other, apron on said rollers, for the purpose specified, sprocket-wheels mounted on the journals of said rollers and having crown-teeth on their inner faces, and an endless sprocket-chain, in combination with hinged pawls located partially within 85 the ends of said rollers and adapted to engage the crown-teeth of said sprocket-wheels, sliding plates, and rods connecting said plates and pawls, all substantially as and for the purposes specified.

In testimony whereof I have signed this specification in the presence of two subscribing witnesses.

CHARLES H. JENNE.
